CLAIM

(21) Appl. No.: **29/161,366**

The ornamental design for a refillable filter bag with ribbon-lock seal for tea or coffee, as shown and described.

(22) Filed: **May 28, 2002**

DESCRIPTION

(51) LOC (7) Cl. **01-01**

FIG. 1 is a perspective view of a refillable filter bag with ribbon-lock seal for tea or coffee embodying the design of the present invention with the ribbon-lock seal in partially opened condition;

(52) U.S. Cl. **D1/199**

FIG. 2 is a front elevational view thereof with the ribbon-lock seal in closed condition;

(58) Field of Search D1/100-129, 199;
426/77-84, 115, 394; 206/0.5

FIG. 3 is a rear elevational view of FIG. 2;

(56) **References Cited**

FIG. 4 is a right side elevational view of FIG. 2, the left side elevational view being a mirror image thereof;

U.S. PATENT DOCUMENTS

FIG. 5 is a top plan view of FIG. 2; and,
